TAPE RECORDER

Wilbur Rizzatti, Hollis, N.Y., assignor to Telectrosonic Corporation, Long Island City, N.Y., a corporation of New York

Continuation of design applications Ser. Nos. 81,368 and 81,385, Aug. 20, 1964. This application Aug. 13, 1965, Ser. No. 86,866

Term of patent 14 years

(Cl. D26—14)

Fig 5

Fig 4

FIGURE 1 is a top plan view of magnetic tape recorder showing one embodiment of my new design.

FIGURE 2 is a right side elevational view of the form of magnetic tape recorder shown in FIGURE 1.

FIGURE 3 is a rear elevational view of the form of magnetic tape recorder shown in FIGURE 2.

FIGURE 4 is a left side elevational view of the form of magnetic tape recorder shown in FIGURE 1.

FIGURE 5 is a top and right side perspective view of the form of magnetic tape recorder shown in FIGURE 1.

FIGURE 6 is a top plan view of a magnetic tape recorder showing another embodiment of my new design.

FIGURE 7 is a right side elevational view of the form of magnetic tape recorder in FIGURE 6.

FIGURE 8 is a rear elevational view of the form of magnetic tape recorder shown in FIGURE 6.

FIGURE 9 is a left side elevational view of the form of magnetic tape recorder shown in FIGURE 6.

FIGURE 10 is a top and front perspective view of the form of magnetic tape recorder shown in FIGURE 6.

The dominant features of my new design are shown by means of full lines of the drawing.

This application is a continuation of each of my prior copending applications, Serial numbers D.81,368 and D.81,385, both filed Aug. 20, 1964, and both now abandoned.

I claim:

The ornamental design for a tape recorder, substantially as shown and described.
